BASE AND OIL RESERVOIR FOR SEWING MACHINES

Wilbur J. Peets, Watchung, N. J., assignor to The Singer Manufacturing Company, Elizabeth, N. J., a corporation of New Jersey

Application May 11, 1950, Serial No. 161,311

7 Claims. (Cl. 112—256)

1

This invention relates to sewing machines, and more particularly to lubricant collecting, conducting, and filtering means associated therewith.

It is well known that lint and dust is deposited in the neighborhood of the feed-dog and stitching instrumentalities of a sewing machine. This is primarily due to the feed-dog rubbing lint from the material being sewed and to the handling of the hook, depending on whether the machine is of the chain-stitch or the lock-stitch type. The various moving parts associated with the feed-dog and the stitch forming instrumentalities must, of course, be lubricated and the lubricant in the neighborhood of the feed-dog and looper or hook, as the case may be, becomes contaminated with the lint and dirt previously mentioned. It is desirable that this excess lubricant be collected, cleaned and returned to the main oil reservoir. Therefore, one of the primary objects of the present invention is to provide an improved means for collecting, conducting and filtering excess oil that may be thrown off by mechanisms in the neighborhood of the feed-dog and stitch-forming instrumentalities of a sewing machine.

Another important object of the invention is to provide an improved means for collecting, conducting and filtering oil of a sewing machine, which means can readily be cleaned or replaced with the minimum of effort and expense.

A further object of the invention is to provide an improved, and at the same time, inexpensive means for collecting, conveying and filtering oil in a sewing machine.

With the above and other objects in view, as will hereinafter appear, the invention comprises the devices, combinations and arrangements of parts hereinafter set forth and illustrated in the accompanying drawings of a preferred embodiment of the invention, from which the several features of the invention and the advantages attained thereby will be readily understood by those skilled in the art.

In the drawings which form a part of this specification;

Fig. 1 is a front elevational view, partly in section, of the bed, base and oil reservoir of a chain-stitch sewing machine embodying the present invention;

Fig. 2 is an enlarged top plan view of one end of the base shown in Fig. 1, the sewing machine having been removed from the base;

Fig. 3 is a vertical sectional view taken on the line 3—3 of Fig. 2;

Fig. 4 is a fragmentary sectional view taken on the line 4—4 of Fig. 2; and

Fig. 5 is a fragmentary perspective view of the oil pan with the oil wick and other parts removed.

The sewing machine in which the present invention is embodied, is fully disclosed in United States Patent No. 2,394,510, issued February 5, 1946. Therefore, it will suffice to say that the sewing machine shown comprises a bed or base 11, affording a horizontally disposed work-supporting plate 12. Preferably a portion of the work-supporting plate is removably secured to the main portion thereof and the removable portion is provided with a throat plate 13 having a conventional needle hole 14 and slots 16, the latter permitting passage of a conventional feed-dog (not shown).

Rising from the right end (Fig. 1) of the work-supporting plate 12 is a hollow standard 17 having formed integral therewith an overhanging bracket-arm (not shown) carrying at its free end a bracket-arm head 18, which movably supports a needle-bar 19 having a needle 21; and the head 18 also supports a presser mechanism 22.

Journaled in the bed 11, beneath the plate 12, is a rotary looper driving shaft 23 which, in a well known manner, imparts lengthwise and sidewise movements to one or more loopers as shown at 24. Other mechanisms of the sewing machine are located in the general area of the looper 24, including a looper supporting and operating mechanism, indicated generally at 25, and a feed dog operating mechanism, not shown. All of these mechanisms are lubricated and excess lubricant thrown off by these mechanisms, is collected by means presently to be described.

The looper actuating shaft 23 is driven in a well known manner through the medium of a pair of bevel gears 26—27. A third bevel gear 28, that meshes with bevel gear 27, drives an oil pump 29, which in a known manner, supplies oil through conduits similar to conduits 31, 32 and through unshown ducts to various parts of the sewing machine much in the same manner as disclosed in Patent No. 2,345,327, issued March 28, 1944.

The mechanisms of the sewing machine, secured to the base 11 and located below the work-supporting plate 12, are enclosed in an oil-pan 41 having vertical end-walls 42 and 43, vertical front and rear walls 44 and 45, respectively, as well as a bottom wall comprising three separate portions, viz a lowermost horizontal bottom portion 46, an inclined center portion 47, and an elevated horizontal end portion 48. The bottom portion

46, together with portions of the front and back walls 44-45, end wall 43 and an intermediate vertical wall 49 forms an oil reservoir 51 from which the pump 29 draws oil. The inclined portion 47 is bounded by a partition or vertical wall 52 and portions of the front and back walls 44 and 45. The elevated portion 48 of the oil pan 41 is located or elevated above the uppermost end of the inclined bottom wall 47 and is bounded on three sides by portions of walls 44-45 and 42 and on the fourth side is bounded by a vertical partition or wall 53 which is parallel to and spaced from the wall 52, thereby forming between the walls 52 and 53 an upwardly open channel 14 for receiving a cork gasket 56. The cork gasket 56 also extends in channels formed parallel to portions of walls 44, 45 above locations where they bound the bottom walls 46 and 47.

The corner (Fig. 2) between the front wall 44 and the end wall 42 is bridged by a bevel wall 57, and the corner between the rear wall 45 and the end wall 42 is likewise bridged by a bevel wall 57'. Protruding from the inner surface of each of these bevel walls, are two vertically extending ribs, each rib being designated 58.

The upper surface of the horizontal bottom wall 48 forms the bottom of an oil drip and equipment enclosing cavity 59 having sides defined by a portion of the front wall 44, the bevel wall 57, the end wall 42, the bevel wall 57', the rear wall 45 and by the partition wall 53. The vertical partition wall 53 (Fig. 4) is of particular interest because its upper edge is irregular in form, having a relatively shallow cut 61 and a deeper cut 62, these cuts providing clearance for various parts of the mechanism carried by and depending from the sewing machine bed 11.

The partition walls 52 and 53 each have deep notches which are connected (Fig. 5) by a passageway 63 having a curved bottom 64 of which the lowermost part is collinear with the upper surface of the bottom wall 48 of the oil drip cavity 59. The bottom wall 48 of the cavity 59 has (Fig. 2) two fenced cavities 66 and 66' for receiving sewing machine leg members, not shown in the drawings, but which depend from the sewing machine base 11. The bottom wall 48 also has a pair of spaced fenced cavities 67 and 67' for receiving short lengths 68 of cork gasket material similar to the gasket 56 hereinbefore described. A pair of upstanding bosses 69 and 69', each of which would be rectangular in form, except that one end of each is curved, as best seen in Fig. 2, rise above the bottom wall 48. Each boss 69 and 69' has an additional upstanding and curved lug portion shown respectively at 71 and 71'.

A substantially oval oil wick 72 parallels the periphery of the oil drip cavity 59. The oval wick 72, with the longest axis of the oval vertical, is held in place adjacent the boundaries of the cavity 59 by a plurality of comparatively thin lugs 73 and by the curved lug portions 71 and 71'. The lugs 73, as well as the curved portions 71-71' rise above the upper surface of the wall 48 a distance that is approximately one-half of the horizontal length of the lugs 73.

Two ends 74 and 74' of the oil wick 72 extend horizontally from the bottom of the cavity 59, through the curved bottom 64 of the passageway 63 and drop (Fig. 1) from the level of the upper surface of the bottom wall 48 to the level of the uppermost end of the inclined bottom wall 47. The wick ends 74 and 74' are of such size that they effectively close the curved bottom of the

passageway 63, thereby preventing free flow of oil from the cavity 59 to the inclined bottom wall 47 and eventually to the reservoir 51. However, the wick by capillary attraction will convey oil that collects in the cavity 59 to the inclined bottom wall 47, and in so conveying the oil, the wick 72 acts as an effective filter to prevent lint and other dirt from passing from the cavity 59 to the reservoir 51.

Both side faces of the passageway 63 (Fig. 5) are channeled as at 76-76', and bases 77-77' of these channels are spaced (Fig. 3) a short distance below the uncompressed height of the wick ends 74 and 74' above the curved bottom 64. The bases 77-77' provide abutments against which the lower edges of the lower face of a small cubical felt block 78 abut. The central portion of the lower face of the block 78 rests on top of the wick ends 74-74', and the cork gasket 56 passes over the upper face of the block 78. As indicated by numeral 79 (Fig. 1), the bed 11 rests on, and thereby depresses a reduced section of the gasket 56 into firm engagement with the block 78, which in turn presses the ends 74-74' of the wick 72 downwardly against the bottom 64 of the passageway 63. The channels 76-76' limit the felt block 78 to vertical movement and the bases 77 of the channels 76 determine the maximum compressing force that may be applied to the wick ends 74-74' by the bed 11.

The path of the oil wick may now be traced (Fig. 2) as follows: One end 74 of the wick 72 protrudes through the passageway 63 and rests on the upper side of the elevated end of the inclined bottom wall 47; it being noted that this upper end is depressed below the bottom 64. From the passageway 63 and the end 74, the wick 72 extends into the cavity 59 past the fenced cavity 67, parallel to the front wall 44, adjacent but spaced from the bevel wall corner 57, parallel to the end wall 42, adjacent but spaced from the second bevel wall 57', then for a short distance in contact with the rear wall 45, around the second fenced leg cavity 66', from whence it jumps to a position adjacent the second fenced cavity 67', thence parallel to the partition wall 53, through the passageway 63, where the second end of the wick is designated as 74'. At frequent intervals within the cavity 59, the wick 72 is held in position against side and other walls by the plurality of lugs 73 and in other places the wick 72 is spaced from the bevel-wall corners 57 and 57' by the ribs 58 and held in position against these ribs by the curved lugs 71.

55 Thus there is provided an inexpensive, and efficient means for collecting excess oil that may be thrown off from parts of a sewing machine, conveying the oil from the cavity in which it was originally deposited and at the same time filtering and purifying the oil.

In the event that the wick 72 becomes clogged, it can easily be removed and cleaned or replaced by a new wick, thus returning the oil conveying and filtering equipment of the sewing machine 65 to its original state of high efficiency.

Having thus set forth the nature of the invention, what I claim herein is:

1. In a sewing machine having a bed with sewing instrumentalities below said bed; an oil pan enclosing the bottom of said bed and said sewing instrumentalities, said oil pan having an oil reservoir and an oil drip cavity, the latter being separated from and having all parts thereof elevated above said reservoir, and said oil drip cavity receiving oil from said sewing instrumen-

talities; and an oil wick of which one portion is positioned in said elevated oil drip cavity, and of which another portion depends below said oil drip cavity and extends toward said reservoir.

2. In a sewing machine having a bed, sewing instrumentalities below said bed, and lubricating means for lubricating said sewing instrumentalities, an oil pan enclosing the bottom of said bed, said sewing instrumentalities, and said lubricating means, said oil pan having an oil reservoir, and an oil drip cavity, the latter having all parts thereof elevated above the level of said reservoir; a wall formed integral with said oil pan and having a passageway, said wall separating said oil drip cavity from said reservoir; and an oil wick of which the main body portion is positioned in said elevated oil drip cavity and of which the ends extend through said passageway and depend toward said oil reservoir.

3. In a sewing machine having a bed, sewing instrumentalities below said bed, and lubricating means for lubricating said sewing instrumentalities; an oil pan enclosing the bottom of said bed, said sewing instrumentalities, and said lubricating means, said oil pan having an oil reservoir, and an oil drip cavity, the latter having all parts elevated above the level of said reservoir; a wall formed integral with said oil pan and having a passageway, said wall separating said oil drip cavity from said reservoir; and an oil conducting and oil filtering wick of which the main body portion is positioned in said elevated oil drip cavity and of which the ends extend through said passageway and depend toward said oil reservoir, the size of said passageway and the size of said oil wick being such that the ends of said oil wick fill the lower end of said passageway, thereby preventing free flow of oil from said drip cavity to said reservoir.

4. In a sewing machine having a bed, sewing instrumentalities below said bed, and lubricating means for lubricating said sewing instrumentalities; an oil pan enclosing the bottom of said bed, said sewing instrumentalities, and said lubricating means, said oil pan having an oil reservoir, and an oil drip cavity, the latter being elevated above the level of said reservoir; a wall formed integral with said oil pan and having a passageway, said wall separating said oil drip cavity from said reservoir; an oil wick of which the main body portion is positioned in said oil drip cavity and of which the ends extend through said passageway and depend toward said oil reservoir; a block positioned in said passageway and pressing on the ends of said oil wick; and means for urging said block downwardly.

5. In a sewing machine having a bed, sewing instrumentalities below said bed, and lubricating means for lubricating said sewing instrumentalities; an oil pan enclosing the bottom of said bed, said sewing instrumentalities, and said lubricating means, said oil pan having an oil reservoir, and an oil drip cavity, the latter being elevated above the level of said reservoir; a wall formed integral with said oil pan and having a passageway, said wall separating said oil drip cavity from said reservoir and providing a pair of vertically extending channels adjacent said passageway; an oil wick of which the main

body portion is positioned in said oil drip cavity and of which the ends extend through said passageway and depend toward said oil reservoir; a cubical block slidably held by said channels and pressing on the ends of said oil wick; a gasket member pressing on said cubical block, and means for urging said gasket downwardly.

6. In a sewing machine having a bed, sewing instrumentalities below said bed, and lubricating means for lubricating said sewing instrumentalities; an oil pan enclosing the bottom of said bed, said sewing instrumentalities, and said lubricating means, said oil pan having an oil reservoir, and an oil drip cavity, the latter being elevated above the level of said reservoir; a horizontally extending bottom wall formed integral with said oil pan and defining the bottom of said oil drip cavity; a plurality of vertical wall members formed integral with said oil pan and defining the sides of said oil drip cavity, one of said wall members having a passageway; an oil conducting and oil filtering wick of which the main body portion is positioned in said oil drip cavity and of which the ends extend through said passageway; and a plurality of lugs upstanding from said horizontally extending bottom wall, said lugs holding said oil wick adjacent said wall members.

7. In a sewing machine having a bed, sewing instrumentalities below said bed, and lubricating means for lubricating said sewing instrumentalities; an oil pan enclosing the bottom of said bed, said sewing instrumentalities, and said lubricating means, said oil pan having an oil reservoir and an oil drip cavity, the latter being elevated above the level of said reservoir; a horizontally extending wall formed integral with said oil pan and defining the bottom of said oil drip cavity; a plurality of vertical wall members formed integral with said oil pan and defining the sides of said oil drip cavity, one of said wall members forming a partition between said oil drip cavity and said reservoir, said partition wall having a passageway and providing a pair of vertically extending channels adjacent said passageway; an oil conducting and filtering wick of which the main body portion is positioned in said drip cavity and of which the ends extend through said passageway and depend toward said reservoir; bases formed at the lower ends of said channels, said bases being slightly below the top of the ends of said wick as they pass through said passageway; a cubical block slidably held by said channels and pressing on the ends of said oil wick; a gasket member pressing on said cubical block; and means for urging said gasket member downwardly.
